United States Patent Office

Des. 195,374
Patented June 4, 1963

195,374

CIGARETTE PACKAGE OR THE LIKE

Gary A. Gerber, 726 Huntington Road,
Bridgeport 10, Conn.

Filed Aug. 22, 1961, Ser. No. 66,457

Term of patent 14 years

(Cl. D58—12.6)

FIG. 4

FIG. 5

FIG. 6

FIG. 2

FIG. 1

The design is characterized by a flat bottom, arcuate upper portion, opposed recesses in the upper portions of the front and back, and ribs on the sides and top portion all as shown.

I claim:

The ornamental design for cigarette package or the like, as shown and described.
